UNITED STATES PATENT OFFICE.

CHARLES H. WOOD AND EDWIN M. BROWN, OF BANGOR, MAINE, ASSIGNORS
TO WOOD, BISHOP & CO., OF SAME PLACE.

DEVICE FOR OPENING STOVE-DOORS.

SPECIFICATION forming part of Letters Patent No. 357,298, dated February 8, 1887.

Application filed May 26, 1886. Serial No. 203,277. (No model.)

To all whom it may concern:

Be it known that we, CHARLES H. WOOD and EDWIN M. BROWN, citizens of the United States, residing at Bangor, in the county of 5 Penobscot and State of Maine, have invented a new and useful Device for Opening Stove-Doors; and we do hereby declare that the following is a full, clear, and exact description of the invention, which will enable others 10 skilled in the art to which it appertains to make and use the same.

Our invention relates to an improved device for opening the doors of stoves without the instrumentality of the hands, and is illustrated in the accompanying drawings, in which—

Figure 1 is an enlarged view of lever detached from the stove. Fig. 2 is a perspective view of stove with lever attached.

20 Similar letters refer to corresponding parts throughout the figures.

Our device consists of a lever, A, pivoted at its upper end to the side of the stove C, behind the door D, upon which it is to operate. Near 25 its lower extremity, projecting behind the back of the stove and preferably extending slightly forward of the side of the stove, is a pedal or foot-piece, a, by means of which the lever is operated by the foot. Upon the edge of the 30 lever nearest the back edge of the stove-door, and so located as to bear upon said back edge, and preferably just beneath the lower hinge, d, of said door, as at the point x, we form a spur, a', having a straight inner edge and a smooth curved outer edge, which edges come 35 to a point and form a species of wedge.

The lever A is pivoted to the side of the stove in such position that the spur a' may bear upon the back edge of the stove-door D, 40 near the bottom thereof; and instead of being pivoted directly to the side of the stove, the lever A is pivoted to a hanger, B, which is screwed or bolted to the side of the stove, as shown in the drawings.

45 The hanger may, if desired, be shaped to fit between the back edge of the stove-door and the vertical bead commonly formed near the back edge of the side of the stove, and can then be secured by a single screw or bolt. By the 50 use of the hanger B the lever A may be made

to swing true on its pivot without wobbling.

In operation pressure is applied to the lever A through the foot upon the pedal a. The lever is thus swung forward and the spur a', bearing upon the back of the stove-door D, 55 near the bottom, pushes the bottom of the door forward, which motion causes the front edge of the door to rise and release the latch n from the catch o. The point of the spur a' enters between the back edge of the stove-door and the stove-body, and the curved outline of the outer edge of the spur wedging the door outward and entering to a point forward of the line of the hinges causes the door to swing round upon the spur until it is wide open. 65

To obtain increased leverage, we bend forward the upper end of the lever, as shown in the drawings, and pivot the lever to the stove or hanger through the forward portion of the bend. 70

The form of spur shown we consider to be the best adapted to the purpose sought to be attained, but is not invariable, as various forms of forwardly-projecting spurs will operate more or less perfectly. 75

Among the advantages of our device may be mentioned the following: It throws the door wide open without the use of the hands. It is applicable to all or nearly all patterns of stoves or ranges without their being especially 80 designed to receive it. It is not in the way, projecting only an inch or two behind the stove. It does not interfere in any respect with the unrestricted use of the oscillating shelves now largely used in front of the oven- 85 doors.

Having thus described our invention, what we claim, and desire to secure by Letters Patent, is—

1. The combination of the stove-body, the 90 stove-door hinged thereto, and a lever pivoted to the side of the stove and formed with a rearwardly-projecting pedal, and a forwardly-projecting spur adapted to be thrust by the movement of the lever against the lower portion of 95 the back edge of the door, and then enter between the stove-door and the stove-body to a point forward of the line of the hinges, substantially as described.

2. The combination of the stove-body, the 100

stove-door hinged thereto, and a lever pivoted to the side of the stove and formed with a rearwardly-projecting pedal and a forwardly-projecting spur with straight rear face and curved front face adapted to be thrust by the movement of the lever against the lower portion of the back edge of the door, and then enter between the stove-door and the stove-body to a point forward of the line of the hinges, substantially as described.

3. The combination of the stove-body, the stove-door hinged thereto, and a lever pivoted to a hanger secured to the body of said stove,

and formed with a rearwardly-projecting pedal and a forwardly-projecting spur adapted to be thrust by the movement of the lever against the lower portion of the back edge of the door, and then enter between the stove-door and the stove-body to a point forward of the line of the hinges, substantially as described. 15
